UNITED STATES PATENT OFFICE.

GUY C. WILKINSON, OF SYRACUSE, NEW YORK, ASSIGNOR TO SYRACUSE WASHING MACHINE CORPORATION, OF SYRACUSE, NEW YORK, A CORPORATION OF NEW YORK.

DRIVING MECHANISM FOR COMBINED WASHERS AND WRINGERS.

Application filed April 29, 1922. Serial No. 557,318.

To all whom it may concern:

Be it known that I, GUY C. WILKINSON, a citizen of the United States of America, of Syracuse, in the county of Onondaga, in 5 the State of New York, have invented new and useful Improvements in Driving Mechanism for Combined Washers and Wringers, of which the following, taken in connection with the accompanying drawings, 10 is a full, clear, and exact description.

This invention relates to a combined washer and wringer operating mechanism involving the use of a vertically reciprocating shaft movable in an opening in the 15 bottom of the washing vat in combination with a frame hinged to swing in a horizontal plane to and from a position over the top of the vat and carrying one or more rollers, which together with the vertical reciprocating shaft are driven from the same source 20 of power, mounted upon the frame of the machine and preferably beneath the vat.

These machines are extensively used in 25 household laundries and kitchens and are mounted upon suitable casters for easy portability from place to place as may be required for more convenient handling of the articles to be laundered, while the motive power preferably consists of an electric motor having a flexible conducting cable carrying 30 a plug for attachment to any of the ordinary incandescent electric lamp-sockets in the room in which the machine is located, and one of the main objects is to distribute 35 the various parts of the driving and driven mechanisms in such manner as to produce a substantially balanced action to avoid excessive vibration and noise when the machine is in operation.

40 Another object is to enable certain parts of the mechanism to be easily and quickly adjusted to accommodate motors of different speeds and at the same time to permit the use of these different motors on the same 45 frame without special fitting.

46 A further object is to simplify the construction and control of the various parts of the machine and at the same time to increase the working efficiency of the various mechanisms.

50 Other objects and uses relating to specific

parts of the mechanism will be brought out in the following description:

In the drawings:

Figure 1 is a vertical sectional view of 55 the machine embodying the various features of my invention, except that portions of the legs are omitted.

Figure 2 is a horizontal sectional view of 60 the same machine just above the vat-supporting platform together with the various mechanisms mounted thereon, a portion of the platform being broken away to disclose certain parts of the underlying mechanism.

Figure 3 is a vertical sectional view 65 through the platform of the frame at right angles to that shown in Figure —1— showing more particularly the operating mechanism for the vertically reciprocating shaft.

The mechanism forming the subject matter of this invention is specially adapted for 70 the operation of a combined washer and wringer and involves the use of a substantially circular horizontal platform —1— supported by a plurality of, in this instance 75 three, legs —2— suitably secured to the periphery of the platform —1— in uniformly spaced relation circumferentially, each leg being provided at its lower end with a caster —3— whereby the entire machine may be 80 easily moved along the floor from place to place to suit the convenience of the operator, the platform and legs constituting a part of the main supporting frame.

A cylindrical vat —4— is supported at 85 the bottom upon the platform —1— for receiving the clothes and similar articles to be washed and is provided with a cover —5— normally in position when the machine is in operation but may be removed 90 and laid aside whenever access to the interior of the vat is required.

An upright tubular post —6— is secured at its lower end to the central portion of the platform —1— coaxial therewith and extends upwardly through a central opening in and some distance above the bottom of the vat and is, therefore, coaxial with said vat. The lower portion of the post —6— is flanged at —7— to rest upon the upper 100 surface of the bottom of the vat, while the portion, which extends through the register-

ing openings in the bottom of the vat and platform is threaded and engaged by a nut —8— cooperating with the flange —7— to firmly clamp the post in place and also serving to clamp the vat to the platform.

A vertical shaft —9— is reciprocally movable endwise and also rotatable in the tubular post —6— through which it extends some distance above the post and also some distance below the platform, said shaft carrying at its upper end the central portion of an upwardly arched yoke —10— having radially extending arms provided with tubular heads —11— for receiving and supporting a pair of inverted cup-shaped dashers —12— for washing purposes.

The central portion of the yoke —10— is provided with a tubular hub —13— slideable upon the upper end of the shaft —9— and adapted to be held in various positions of adjustment by a locking pin —14—, which is adapted to enter a series of diametrically extending apertures —15— in said shaft. That is, the locking bolt —14— is slideable in registering diametrical openings in the hub —13— and shaft —9— and is provided with annular grooves —16— and —17— for receiving a detent —18— Figure 9, said detent being urged toward the periphery of the locking bolt by means of a spring —16'—, the tension of which may be adjusted at will through the medium of a screw —17'—.

The annular grooves —16— and —17— are spaced apart axially a distance greater than the diameter of the shaft —9— while the detent —18— and its adjusting means including the spring —16'— and screw —17'— are arranged in a socket in one side 40 of the hub —13— radial to the bolt to permit the bolt to be withdrawn from its locking position a distance equal to the distance between the annular grooves —16— and —17— and thereby to permit the vertical adjustment of the yoke —10— relatively to the shaft —9— according to the quantity of clothes operated upon in the vat.

An additional upright tubular post —19— extends vertically along the outside of the vat —4— in close proximity to one of the legs —2— parallel with the tubular post —6— and has its lower end seated in a socket —20— of a gear case —21— and its upper end extended through a bearing member —22— on the adjacent side of the vat to receive a vertical shaft —23—. The gear case —21— is secured to the under side of the platform —1— and together with the bearing member —22— forms a part of the main supporting frame, the bearings —20— and —22— being provided with set screws —24— by which the tubular post —19— may be rigidly secured thereto against rotation or relative endwise movement.

65 A supplemental frame —25— is provided

at one end with a gear case —26— having a hub —27— which is journaled upon the upper end of the tubular post —19— to swing horizontally to and from a position over the top of the vat —4— for receiving and supporting a pair of wringer rolls —27'— and permitting the clothes to be wrung in any position of adjustment.

The object in placing the supporting post —19— for the wringer frame in close proximity to one of the legs of the main supporting frame is to prevent overbalancing of the machine by the weight of the wringer particularly when the latter is swung outwardly to one side of the vat, thereby avoiding the necessity for extra supporting means.

The central or inner shaft —9— carrying the yoke —10— and dashers —12— is reciprocated vertically for washing purposes and is intermittently rotated to change the angular position of the dashers to operate upon all parts of the clothes in the vat, while the outer shaft —23— is adapted to be rotated and is geared to one of the wringer rolls —27'— for wringing purposes. Both of these shafts are operated from the same source of power, as for example, an electric motor —28— through the medium of suitable gearing which together with the motor are mounted upon the under side of the platform —1— of the main supporting frame in such manner as to approximately balance the weight and load and thereby to reduce to a minimum the vibration of the machine when in operation which is highly important in machines of this character owing to the fact that they are commonly used in household kitchens and laundries where excessive vibration and noise would be extremely annoying.

In other words, I have sought to distribute the motor and power transmitting mechanism to the washer and wringer more evenly around the axis of the vat or main supporting frame and thereby to reduce not only the vibration, noise and wearing of the operating parts but also to enable the machine to stand more steadily in one position without fastening it to the floor or other support, all of which contribute materially to the successful operation of the machine.

For this purpose, the motor —28— and its armature shaft —29— are disposed in a horizontal position at one side of the central vertical shaft —9— and is connected by suitable gearing to a horizontal counter shaft —30— which is mounted in suitable bearings on the under side of the platform —1— at the opposite side of the central vertical shaft —9— and parallel with the driving shaft —23—.

This balanced distribution of the various mechanisms, as shown more clearly in Figure 2, is further carried out by placing the relative heavy motor —28— at one side of

the central shaft —9— while the gearing for transmitting motion from the driving shaft —29— to the counter shaft —30— together with the wringer supporting post —19— and outside vertical shaft —23— are carried by the main supporting frame at the opposite side of the central vertical shaft, thereby causing the entire machine to stand with approximately equal firmness upon all 10 three legs and reducing to a minimum the vibration and noise as well as wear incidental to the operation of the machine.

The gearing for transmitting motion from the motor shaft —29— to the counter shaft —30— is mounted in a suitable gear case —31— which is secured to the under side of the platform —1— at one side of the central shaft —9— opposite to that at which the motor —28— is located. The outer end of 20 the motor shaft —29— is journaled in the gear case —31— and owing to the fact that the gear case and motor case are secured by separate fastening means to the under side of the platform, the motor shaft is preferably made in sections coupled together end to end by a universal joint —32— to compensate for any slight variation in the alignment of the shaft sections in the event that the bearings for the motor shaft in the gear 25 case and motor case should be slightly out of alignment after those cases have been secured to the frame.

It will be observed, however, that provision is made for adjustment of the motor case upon the platform —1— not only to enable the motor to be properly aligned with the shaft bearing in the gear case —31— but also to permit the use of different speed 30 motors and for this purpose, the portions of the platform —1— to which the motor is secured, is provided with slots —33— and —34—, those of each set being elongated at an angle to those of the other set to receive the clamping bolts as —35— by which the 45 motor is fastened to the frame.

The gearing in the case —31— is arranged to transmit continuous rotary motion from the shaft —29— to the shaft —30— and comprises a pinion —36— on the shaft 50 —29— meshing with a gear —37— to which is secured a coaxial pinion —38— meshing with a relatively large gear —39—, the gear —37— and its pinion —38— being journaled in separate sections of the case —31—, while the gear —39— is splined on the counter shaft —30— to slide endwise thereon and at the same time to impart rotary motion thereto.

A tubular shaft section or sleeve —40— is 60 journaled in one side of the gear case —31— coaxial with and adapted to receive the adjacent end of the counter shaft —30— to form a continuation thereon. This sleeve is provided with an enlarged inner end or head —41— engaging the inner face of the

adjacent wall of the case —31— to hold the sleeve against outward displacement and is provided with a series of clutch pins —42— adapted to enter corresponding apertures —43— in the gear —39— as the latter is 70 moved endwise into engagement therewith and thereby to lock the sleeve to the shaft —30—.

The hub of the gear —39— is provided with an annular groove —44— for receiving 75 the forked end of a shifting member —45— which is slidably mounted in the adjacent side of the gear case —31— and is pivotally connected at —46— to one end of a shifting lever —47—, the latter being pivoted at 80 —48— to the case —31— and having its other end connected by a link —49— to a crank shaft —50—.

This crank shaft extends vertically along the outside of the vat —4— near the tubular 85 post 19 and has its lower end journaled in a bearing —51— on the platform —1— and provided with a crank arm —52— for receiving the adjacent end of the link —49—, while the upper end extends to approximately 90 the top of the vat and is provided with a hand piece —53— by which the shaft —50— may be turned at will to throw the clutch gear —39— into and out of engagement with the clutch sleeve —40—.

The outer end of the sleeve —40— is provided with a crank arm —54— connected by a link —55— to the intermediate portion of a lever —56— which extends at right angles to and in a plane below the axis of the crank shaft —40— radially to the vertical shaft —9— and has its inner end pivotally connected at —57— to a collar —58— on said shaft for imparting vertical reciprocatory movement thereto, the outer end of said lever being connected by a swinging link —59— to the under side of the platform —1— as shown in Fig. 3.

A nut —60— on the lower end of the shaft —9— holds the collar —57— against downward displacement, while the upward displacement is prevented by a ratchet wheel —62— secured to the shaft —9— just above the collar.

A rock arm —63— is journaled on the shaft —9— just above the ratchet wheel —62— and is provided with a pawl —64— spring pressed into engagement with the teeth of the ratchet wheel —62— to rotate the shaft as the rock arm —63— is turned angularly in one direction and to permit the rock arm to return independently of the ratchet wheel.

The means for operating the rock arm 125 —63— about the axis of the shaft —9— consists of an upward slotted extension —65— of the lever —56— and a pin —66— extending radially from the hub of the rock arm —63— into a vertically elongated slot —67— in said extension whereby during 130

the vertical movement of the shaft —9— by the lever —56—, the extension —64— will be rocked transversely of the axis of said shaft and thereby effect a partial rotation of the shaft and washer mechanism carried thereby during the upward stroke of the shaft or while the dashers are free from engagement with the clothes.

It is now evident that when the clutch gear —39— is shifted into interlocking engagement with the shaft section —40—, vertical reciprocatory and also rotary motion will be transmitted from the motor shaft —29— to the vertical shaft —9— and that the withdrawal of the clutch gear —39— from interlocking engagement with the shaft section —40— will cause the operation of the shaft —9— to cease, while the shaft —30— and outside vertical shaft —23— will continue to rotate.

The lower roller —27— in the frame —25— is provided with a beveled gear —68— within the gear housing —26—, while the shaft —23— is provided with connected beveled gears —69— splined or feathered thereon to be moved from a neutral position into and out of engagement with opposite sides of the beveled gear on the lower roller —27— by means of a shifting lever —70— for reversing the operation of the wringer rollers in any position of adjustment of the frame —25—, which latter is held in different angular positions by means of a locking bolt —71— entering anyone of a series of radial openings in the post —19— and operable at will.

Rotary motion is transmitted from the counter shaft —30— to the outside vertical shaft —23— by means of beveled gears —72— within the housing —21— which latter is connected to the gear case —31— by means of a tubular sleeve —73— surrounding the intermediate portion of the shaft —30— as shown in Figure 1. The end of the gear case —31— adjacent the pinion —36— is provided with a removable cap —36'— to permit access to the interior of the case and also the use of pinions of different sizes to maintain the desired speed of operation of the washer and wringer mechanism with different speed motors.

An automatic switch —75— is mounted upon the base —1— and connected in the motor circuit between the motor and source of power for automatically breaking the circuit in case of overload upon the motor

to prevent injury to the motor and mechanisms actuated thereby, said switch being of any well known construction not necessary to herein illustrate or describe.

In operation, the movement of the shifting lever —50— in one direction from a neutral position will cause the gear clutch —39— to be shifted from a corresponding neutral position into clutching engagement with the sleeve or shaft section —40— to reciprocate the shaft —9— vertically for washing purposes during which operation, the shaft will be rotated intermittently in one and the same direction through the medium of the pawl —64— and ratchet —62—, while the outside vertical shaft —23— will also be rotated to operate the wringer mechanism in either direction by simply shifting the lever —70— from a neutral position to one or the other of its operating positions but under all conditions, the load and torque of the vertical shaft operating mechanism will be substantially balanced and thereby to reduce to a minimum the vibration and noise of the machine and cause the machine to be supported with equal pressure upon each of its legs and by reason of this balanced condition, the machine, although mounted on casters, will maintain its one position upon the floor without liability of shifting around from one place to another.

What I claim is:

Driving mechanism for a combined washer and wringer including an upright washer-operating shaft and an upright wringer-operating shaft, and comprising a gear case having spaced parallel horizontal bearings at opposite sides of the washer-operating shaft, a motor driven shaft journaled in one of said bearings, a motor having its armature shaft alined with and connected to the motor driven shaft, a counter shaft journaled in the other bearing, said motor driven shaft and counter shaft being located at opposite sides of the washer-operating shaft, means within the gear case for transmitting rotary motion from the motor driven shaft to the counter shaft, means including a clutch within the gear case for transmitting motion from the counter shaft to the washer-operating shaft and additional means for transmitting motion from the counter shaft to the wringer shaft.

In witness whereof I have hereunto set my hand this 24th day of April 1922.

GUY C. WILKINSON.
